[57] CLAIM

The ornamental design for a truck visor, as shown and described.

DESCRIPTION

FIG. 1 is a perspective view of a truck visor showing our new design, it being understood that the broken lines are for illustrative purposes only to illustrate the environment the visor will be used in;

FIG. 2 is a side elevational view thereof;

FIG. 3 is a rear elevational view thereof;

FIG. 4 is a front elevational view thereof;

FIG. 5 is a top plan view thereof;

FIG. 6 is a bottom plan view thereof;

FIG. 7 is a vertical sectional view taken substantially along line 7—7 of FIG. 3; and

FIG. 8 is a vertical sectional view taken substantially along line 8—8 of FIG. 3.

FIG. 7

FIG. 8

FIG. 4

FIG. 5

FIG. 6
